TIME-DELAY RELAY MECHANISM

John S. Baker, Chicago, Ill., assignor to Cook
Electric Company, Chicago, Ill., a corporation
of Illinois

Application July 16, 1945, Serial No. 605,416

8 Claims. (Cl. 175—320)

1

This invention relates to electrical time delay apparatus and more particularly to electrical time delay relays for producing relatively prolonged time delay intervals, it being an object of the invention to provide improved time delay apparatus of the character indicated.

It is a further object of the invention to provide improved electrical time delay relays for producing a plurality of time delay intervals.

It is a further object of the invention to provide an improved time delay relay.

Electric time delay relays are small units having coils or windings to actuate an armature which in turn functions to open or close contacts associated therewith. Time delays are produced in the operation of the contacts, whether opening or closing, by well known means which commonly comprise magnetically coupling short-circuited windings or slugs with the relay exciting windings which delay the increase or decrease of current in the relay windings according to well known laws, such short-circuited windings usually being placed on the same magnetic core as the exciting windings. The relay armature is attracted to actuate the contacts only when the current through the coil reaches a certain value. Thus by varying the time necessary to reach this value the time delay of the relay is varied. Prior expedients to vary the time delay involve increasing the inductance of the relay windings without substantially increasing the resistance, and apparatus constructed according to such well known principles are capable of only producing relatively short time delays. Moreover, apparatus constructed according to these principles becomes bulky when relatively prolonged time delays are desired, and consequently, it is not satisfactory where design requirements dictate a unit of small size. Accordingly, it is a further object of the invention to provide an improved electrical time delay relay for producing a relatively prolonged time delay interval that is small in size, efficient in operation and simple to use.

In carrying out the invention in one form, time delay apparatus is provided which comprises a plurality of time delay circuits adapted to be energized in succession and contacts associated with each of said plurality of circuits. The contacts associated with a particular circuit

2

are adapted to be energized by that circuit after a time delay, and each circuit is energized through a pair of contacts operated by a preceding circuit. More particularly, the time delay apparatus comprises a first pair of time delay circuits having an armature operable thereby with limits of movement, a second pair of time delay circuits having an armature operable thereby also with limits of movement, resilient means resisting operation of the first armature, and resilient means resisting operation of the second armature. Energization of the first one of the first pair of time delay circuits operates the first armature against the first resilient means to a position intermediate its limits of movement. First contacts are adapted to be actuated by the first armature in its intermediate position to energize the first one of the second pair of time delay circuits and energization thereof operates the second armature against the second resilient means to a position intermediate its limits of movement. Second contacts are adapted to be actuated by the second armature in its intermediate position to energize the second one of the first pair of time delay circuits to further operate the first armature against the first resilient means to one limit of its movement. Third contacts are adapted to be operated by the first armature at this limit of movement to energize the second of the second pair of time delay circuits to further operate the second armature against the second resilient means to one limit of its movement. Contacts for controlling an external circuit are arranged to be operated by the second armature at this limit of movement.

For a more complete understanding of the invention, reference should now be had to the accompanying drawings in which:

Figure 1 is a front elevational view of a relay embodying the invention;

Fig. 2 is an end elevational view partially in section of Fig. 1;

Fig. 3 is a somewhat enlarged sectional elevational view taken substantially along lines 3—3 of Fig. 2;

Fig. 4 is a sectional elevational view taken substantially along lines 4—4 of Fig. 2;

Fig. 5 is a sectional elevational view taken substantially along the lines 5—5 of Fig. 3;

Fig. 6 is an enlarged view taken substantially along the lines 6—6 of Fig. 3 with circuits and connections thereto shown diagrammatically;

Fig. 7 is a schematic wiring diagram showing the manner of operation of the relay;

Fig. 8 is a similar wiring diagram of another embodiment of the invention;

Fig. 9 is a schematic diagram showing a further manner of obtaining a time delay;

Fig. 10 is a schematic diagram showing another manner of obtaining a time delay, and

Fig. 11 is a schematic diagram showing a still further manner of obtaining a time delay.

Referring more particularly to the drawings, the invention is shown embodied in a relay 10 including a casing or housing 11, time delay adjusting means 12 and 13 mounted on one side of the housing, a terminal board 14 mounted on the other side of the housing, and time delay means mounted inside of the housing, as will be more particularly described.

The housing 11 may be of any desirable form having sufficient rigidity to support the operating elements and may, for example, include a base 16, front and rear side walls 17 and 18, and a cover 19. The side walls 17 and 18 are connected by a bottom portion 21 which is received between the ends of the base 16 and bolted thereto as shown, so that the front and rear walls 17 and 18 extend upwardly, the time delay adjusting means 12 and 13 extending outwardly of the front side wall 17, and the terminal board 14 being mounted on the rear wall 18. To completely enclose the relay housing, the cover 19 is substantially inverted U-shaped, having ends 22 and 23 connected by a top portion 24, the ends and top portion being U-shaped in cross section thereby to provide extending flanges 25 and 26 which are received around the side walls 17 and 18. The cover 19 is attached to the base 16 by means of screws 27 and 28.

Mounted inside of the relay casing 11 to produce the time delays are two time delay units 29 and 31, each of which is capable of producing two time delay intervals. Through circuits and contacts to be described, these separate time intervals are added to each other to produce a prolonged time delay.

The time delay unit 29 is a relay having contacts adapted to be operated by a coil which embodies time delay means within it and includes a frame 32, a coil 33 attached to the frame at one end thereof, an armature 34 pivoted to the frame at the other end and arranged to be attracted by the coil when energized, and two series of contacts 37 and 38 mounted on the frame. The armature 34 is provided with a pair of arms 35 and 36 (Fig. 5) extending along the sides of frame 32 and provided with right angularly extending tongues 57 and 58 for actuating the contacts. The series of contacts 37 comprises the contact springs 39, 41, 42, 43 and 44, which are separated from each other by suitable insulators 45, the assembly of contact springs and insulators being attached to the relay frame by means of bolts 46. Each contact spring is provided with an arc-resisting contact whereby external circuits are either completed or broken when armature 34 is attracted by coil 33. The contact springs 39, 42 and 44 are arranged to be relatively stationary, whereas contact springs 41 and 43 are provided with insulating nipples 47 and 48 respectively, by means of which these contact springs are operable by the armature 34. The contact spring 41 is provided with two contacts as shown (Fig. 3)

and cooperates with the contact spring 39 to form an initially closed circuit and further cooperates with contact spring 42 to form an initially open circuit. The series of contacts 38 comprises the contact springs 49, 51, and 52 separated from each other by means of suitable insulators 53 and attached to the frame 32 by means of bolts 54. The contact springs 49, 51, and 52 are provided with suitable arc-resistant contacts, the contact spring 51 being provided with two contacts as shown and having an insulating nipple 50 attached thereto for engagement by the tongue 58 (Fig. 4) whereby the contact spring 51 cooperates with contact spring 52 to form an initially open circuit, and further cooperates with contact spring 49 to form an initially closed circuit.

The two series of contacts 37 and 38 are separated from each other by means of an insulating spacer 55. The armature 34 is pivoted to the relay frame 32 by an attaching plate 56 held to the frame 32 by means of bolts 46 and 54 which also hold the contact springs to the frame. Lying directly on top of the attaching plate 56, and overlying tongues 57 and 58, are the armature movement resisting springs 59 (Fig. 3) and 61 (Fig. 4). The armature resisting springs 59 and 61 bias the armature to its initial or inoperative position and resist any changes therefrom when it is attracted by energizing coil 33. Movement of the armature is also resisted by the resilient contact springs 41, 43 and 51, as shown.

The coil 33 comprises an iron core 62 and four windings 63, 64, 65 and 66 (Fig. 7). The winding 63 is connected to terminals 67 and 68 (Fig. 3) and the winding 64 is connected to terminals 69 and 71 (Fig. 4) whereby these two windings may be energized from an external source of current. The windings 65 and 66 associated respectively with windings 63 and 64 are short-circuited on themselves, whereby time delays are produced in the building up of the magnetic field through the iron core 62. The number of turns in and the resistance of the coils 63 and 64 may have suitable values to produce the necessary attractive force to operate the relay contacts, and the number of turns in and the resistance of the coils 65 and 66 may have suitable values to produce the necessary time delays desired, as is well understood by those skilled in this art.

The time delay unit 31 similar to the time delay unit 29 is a relay having contacts adapted to be operated by a coil embodying time delay means within it, and includes a frame 72, a coil 73 attached to one end thereof, an armature 74 pivoted to the other end thereof, and two series of contacts 75 (Fig. 3) and 76 (Fig. 4) insulated from each other by an insulating spacer 78 (Fig. 6). The armature 74 is pivoted to the frame 72 by a shaft 77 so as to be attracted by coil 73 when energized, the shaft being held to the frame 72 by means of a plate 78. A pair of arms extend from armature 74 along each side of frame 72, the arms being provided with lugs 79 and 81 for actuating the contacts. The series of contacts 75 comprises the contact springs 82, 83, 84, 85 and 86 separated from each other by suitable insulators 87 and attached to the frame 72 by means of bolts 88. Each of the contact springs is provided with an arc-resistant contact as shown whereby external circuits may be completed or broken by actuating contact springs 83 and 85 through movement of armature 74, insulating nipples 89 and 91 being attached respectively to contact springs 83 and 85 for this pur-

pose. The contact springs 82, 84 and 86 are arranged to remain relatively stationary while the contact springs 83 and 85 are movable, the contact spring 83 being provided with two contacts (Fig. 3) whereby it cooperates with the contact spring 82 to form an initially closed circuit, and with the contact spring 84 to form an initially open circuit.

The series of contacts 76 includes the contact springs 92, 93, 94, 95 and 96 separated from each other by means of insulators 97 and attached to the frame 72 by means of bolts 98. Each of these contact springs is provided with an arc-resistant contact whereby through actuation by the armature 74 external circuits may be completed or broken as desired, the contact springs 92, 94 and 96 being adapted to remain relatively stationary while contact springs 93 and 95 respectively are provided with insulating nipples 99 and 101, which are engaged by the armature tongue 79 to move these contact springs for circuit making or breaking purposes. The contact spring 93 is provided with two contacts as shown (Fig. 4) whereby it cooperates with contact spring 92 to form an initially closed circuit and further cooperates with contact spring 94 to form an initially open circuit.

Lying directly on the attaching plate 88, and overlying tongues 79 and 81 of armature 74, are the armature movement resisting springs 102 (Fig. 3) and 103 (Fig. 4) respectively. The springs 102 and 103 are held to the frame 72 by the bolts 88 and 98 holding the series of contacts 75 and 76 to the frame 72, and resiliently resist movement of armature 74 when coil 73 is energized. The contact springs 93 and 95 bearing against the tongue 79 and the contact springs 83 and 85 bearing against the tongue 81 also resist movement of the armature.

The coil 73 similar to the coil 33, includes an iron core 105 and four windings 106, 107, 108 and 109 (Fig. 7), the winding 106 being connected to the terminals 111 and 112 (Fig. 3), and the winding 107 being connected to the terminals 113 and 114 (Fig. 4), whereby these windings may be connected to an external source of current. The windings 108 and 109 are short-circuited on themselves to produce time delays in the building up of a magnetic field through the core 105 and consequently in the operation of the armature 74 after coils 106 and 107 are energized. The number of turns in and the resistance of windings 106 and 107 are such as to produce a magnetic force of the magnitude desired to attract armature 74, and the resistance and the number of turns in the windings 108 and 109 are such as to produce the desired time delay in connection with the windings 106 and 107 as is well understood by those skilled in this art.

The time delay units 29 and 31 comprise externally excited coils wound on iron cores and short-circuited windings magnetically coupled therewith. It is well known that when a circuit having both resistance and inductance is supplied with a direct current voltage, the current in that circuit increases from zero to a steady state or maximum value according to the law

$$i = I(1 - e^{-\frac{RT}{L}})$$

where i is the current in the circuit at any time T , I is the steady state or maximum current value, R is the total resistance in the circuit, L is the total inductance in the circuit, and e is the base of the Napierian system of logarithms. By

varying the values of resistance and inductance, the time necessary for the current in the circuit to build up to any value may be varied. If the ratio R/L is small, the current i increases slowly and if the ratio is large, the current i increases at a more rapid rate. While the law for direct current excitation has been given, it will be understood that alternating current may of course be used.

Referring to Fig. 7 where the time delay units 29 and 31 are shown schematically with their windings to be externally energized and their associated short-circuited windings, if the winding 106 is energized, current begins to flow therein dependent on its own resistance and inductance, and also on the resistance and inductance reflected into the circuit by the coupled short-circuited windings 108 and 109, according to the law previously set forth. While the current in winding 106 is increasing, there is current flowing in windings 108 and 109 by virtue of the magnetic coupling, but when the current in winding 106 reaches its steady state value the current in windings 108 and 109 is reduced to zero. The time delay between the energization of the winding 106 and the building up of the current therein to substantially its maximum value is the time delay produced by winding 106, and contacts associated with the winding are operated at the end of that time interval.

The winding 107 of time delay unit 31 and the windings 63 and 64 of time delay unit 29 are not energized at the time the winding 106 is energized. However, when the winding 107 is energized, a time interval elapses between the energization thereof and the building up of the current therein to its maximum value according to the law set forth. The resistance of the coil 107, the inductance thereof, as well as the resistance and inductance reflected into the circuit by the short-circuited windings 108 and 109 enter into producing the time delay as already pointed out for winding 106. Similar to the time delay unit 31, there is a time delay between energizing each of the coils 63 and 64 of the time delay unit 29, and the increase of current therein to its maximum or steady state value, the coupled short-circuited windings 65 and 66 being provided as part of the time delay means. Through appropriate circuits and contacts operated by the time delay units 29 and 31, the various coils are energized in succession. The winding 106 is energized first and after the current therein has increased to a certain value, contacts 95 and 96 are closed to energize the winding 63. After the current in winding 63 has increased to a certain value, contacts 43 and 44 are closed to energize the winding 107. After the current in winding 107 has increased to a certain value, contacts 85 and 86 are closed to energize the winding 64 which, after a time interval, has sufficient current flowing through it to close associated service or like contacts on contact springs 41 and 42. Thus by energizing the various coils of the time delay units in succession, each succeeding coil being energized by contacts controlled by the preceding coil, a total time delay equal to the sum of the individual time delays is obtained.

As already pointed out, varying the resistance in the circuits of the windings varies the elapsed time between the energization thereof and the increase of the current therein to its maximum value. Therefore the variable resistors 115 and 116 are associated respectively with the time delay mechanisms 31 and 29. The resistor 115

is part of a resistance unit which may be of any well-known type including a fixed terminal 117 attached to one end of resistor 115, and a movable arm 118 connected to a stationary terminal 119, whereby moving arm 118 varies the amount of resistance 115 included in the circuit, the arm 118 being turned by the adjusting knob 13. The resistor 116 is also part of a well-known resistance unit including a fixed terminal 121 connected to one end thereof and a rotatable arm 122 adapted to move along the resistor 116 to vary its value. The movable arm 122 is connected to the stationary terminal 123 and is rotatable through the adjusting knob 12.

Referring to Figs. 6 and 7, in order to energize coil 106 a circuit is completed extending from a source of supply, through conductors 124 and 125 to the terminal 111 and through conductors 126 and 127 to the terminal 112. After current of sufficient value flows through winding 106, the armature 74 is attracted to close the contacts on contact springs 95 and 96, energizing winding 63 through a circuit extending from the source of supply through conductor 124, conductor 128, terminal 69, through winding 63, terminal 71, conductor 129, contact springs 96 and 95, conductor 131, conductor 132, and conductor 126 to the source of supply. When the current in winding 63 rises to the necessary value, the armature 34 is attracted to close the contacts on contact springs 43 and 44, thereby energizing winding 107 through a circuit extending from the source of supply, through conductor 124, conductor 133, resistor 115, conductor 134, contact springs 43 and 44, conductor 135, terminal 113, through winding 107, terminal 114, conductor 136, conductor 132, and conductor 126 to the source of supply. After a time interval, sufficient current flows in the winding 107 to further attract armature 74 to close the contacts on the contact springs 85 and 86 which energizes the winding 64 through a circuit extending from the source of supply, through conductor 124, conductor 128, conductor 130, resistor 116, conductor 137, contact springs 85 and 86, conductor 138, terminal 68 through coil 64, terminal 61, conductor 139 and conductor 126 to the source of supply. After the current in winding 64 reaches substantially its maximum value the armature 34 is further attracted to close contacts of springs 41 and 42 associated with external circuits which experience the additive time delays produced by each winding.

To supply power to the time delay units 29 and 31, as well as to provide connections to external circuits whereby the different time delays available from the time delay units may be made use of, the terminal board 14 is provided with a plurality of terminals 141, 142, 143, 144, 145, 146, 147, 148, 149, 150, 151, 152, 153, and 154, each of the terminals being supported by means of a suitable grommet 155. Circuits from the terminals 141-152, inclusive, to the contact springs are completed as follows: from terminal 141, through conductor 155 to contact spring 41; from terminal 142, through conductor 157 to contact spring 39; from terminal 143, through conductor 158 to contact spring 42; from terminal 144, through conductor 159 to contact spring 49; from terminal 145, through conductor 161 to contact spring 51; from terminal 146, through conductor 162 to contact spring 52; from terminal 147, through conductor 163 to contact spring 93; from terminal 148, through conductor 164 to the contact spring 94; from terminal 149,

through conductor 165 to contact spring 92; from terminal 150, through conductor 166 to contact spring 84; from terminal 151, through conductor 167 to contact spring 83; from terminal 152, through conductor 168 to contact spring 82; from terminals 153 and 154, the conductors 124 and 126 extend respectively for supplying power to the time delay units.

With the foregoing structure in mind, it is believed that the functioning of the invention may best be understood by considering an example of operation. It is assumed that the source of power, which may be a battery 169 (Fig. 7), is connected to terminals 153 and 154 (Fig. 6) through a switch 171, and that external circuits are connected to the various terminals as may be desired. While the source of power 169 has been shown as a direct current source, it will be understood that alternating current may be used without departing from the spirit and scope of the invention. Then, if the switch 171 is closed at any instant, power is supplied to the winding 106 through its terminals 111 and 112 and the conductors 125 and 127 already described. At this instant none of the remainder of the windings have any external energization applied to them since the circuits leading to them are open. The current increases through the winding 106 at a rate dependent on the circuit constants as previously indicated and consequently builds up a magnetic field through the core 185, which tends to attract the armature 74. The movement of the armature, however, is resisted by the springs 102 and 103 as well as by contact springs 83, 85, 93 and 95 which bear against the armature through the attached insulating nipples. However, when the current through winding 106 approaches its maximum or steady state value, the armature 74 is attracted sufficiently to move against the force of springs 102 and 103 and the contact springs a small amount sufficient to close the contacts of contact springs 95 and 96 without closing the contacts of contact springs 85 and 86. This movement of the armature also opens the contacts of the contact springs 92 and 93 and closes the contacts of contact springs 93 and 94, but contact springs 82, 83 and 84 are so positioned that the contacts associated therewith do not have their relative positions changed. The resisting force of the springs 102 and 103, along with that of the various contact springs, is balanced against the attractive force produced by the winding 106. The point of balance, i. e., where the armature becomes stationary, may be so adjusted that operation of the contacts occurs a fraction of a second after the switch 171 is closed, for example, after a time interval of the order of one-tenth to three-tenths seconds, but since the armature is not completely attracted, all of the contact springs associated therewith are not actuated. However, external circuits connected to the terminals 147 and 148 are closed and external circuits connected to the terminals 147 and 149 are opened after the time delay effected by the winding 106 (the first time delay of unit 31), since movement of the contact spring 93 effects movement of its contact away from the contact of contact spring 92 and into contact with the contact of contact spring 94.

After the contacts of contact springs 95 and 96 are closed, the winding 63 of the time delay unit 29 is energized through the circuit already described. The current increases through the winding 63 at a rate determined by the associated

circuit contacts, and accordingly a magnetic field is built up through the iron core 62 which tends to attract armature 34. Movement of armature 34 is resisted by springs 59 and 61 as well as of the contact springs 41, 43 and 51 through attached insulating nipples bearing against the armature. As the current in coil 63 approaches its maximum or steady state value, the armature is attracted with sufficient force to overcome the force of the resisting springs to effectuate closing of the contacts of contact springs 43 and 44. At the same time, the armature 34 opens the contacts of contact springs 39 and 41 and closes the contacts of contact springs 41 and 42. Other contact springs associated with the time delay unit 29 are positioned so as not to be effected by this initial movement of the armature. The attractive force produced by the winding 63 is balanced against the resisting force of the springs and the armature becomes stationary when these forces are equal, which condition exists after a movement of the armature sufficient to operate contacts of contact springs 30, 41 and 42 as well as of contact springs 43 and 44. The effect of the resisting force is to delay actuation of these contacts for a period of the order of one-tenth to three-tenths seconds, for example, which time delay is added to the time delay produced by the winding 106. Therefore the external circuits connected to the terminals 141 and 142 (contact springs 30 and 41), and terminals 142 and 143 (contact springs 41 and 42), are opened and closed, respectively, after a time delay of the order of four-tenths to six-tenths of a second, for example.

Closing the contacts of contact springs 43 and 44 energizes winding 107 through a circuit already described including the resistor 115. With the completion of this circuit, current begins to flow through the winding 107 as well as through the windings 108 and 109 which are inductively coupled to the winding 107 by being wound on the same iron core. The current through winding 107 increases as determined by the associated circuit constants, and as it increases the magnetic field created thereby through the iron core 105 also increases, and when this current reaches substantially its maximum or steady state value, the armature 74 is attracted to its final position thereby closing the contact springs 85 and 86. Movement of armature 34 is also resisted in this instance, as in the instance of energizing winding 106, by the armature resisting springs 102 and 103 as well as by the contact springs 83, 85, 93 and 95, and the time delay between the energization of winding 107 and the closing of the contacts of contact springs 85 and 86 is the result of the attractive force produced by the magnetic field through core 105, and the resisting force produced by the springs 102 and 103 as well as of the contact springs associated with the armature 74. The winding 106 is still energized and thus the final movement of armature 74 is the result of the combined efforts of windings 106 and 107. This final movement of the armature 74 in addition to closing the contacts of contact springs 85 and 86, closes the contacts of contact springs 83 and 84 as well as opening the contacts of contact springs 82 and 83. The time delay produced through the energization of winding 107 is added to the time delays produced by windings 106 and 63, and, therefore, external circuits connected to the terminals 151 and 152 (contact springs 82 and 83) and 150 and 151 (contact springs 84 and 83) will be actuated after a time delay of seven-

tenths to nine-tenths of a second (the time delay occasioned by winding 107 being of the same order of magnitude as that produced by winding 106). Through the use of the variable resistor 115, variations in the time delay produced by winding 107 of the order of one-tenth to three-tenths seconds, for example, may be realized.

Closing the contact springs 85 and 86 completes the energizing circuit for winding 64 through a circuit already described including the variable resistor 116, and with the completion thereof current begins to flow therein and increases at a rate which is dependent on the associated circuit constants according to the law set forth. As current through winding 64 increases, the magnetic field created by it through core 62 also increases and attracts the armature 34 to its final position, movement thereof being resisted by the armature resisting springs 59 and 61 as well as by the contact springs 51, 41 and 43 similar to the case of energizing the winding 63. The winding 63 is still energized and thus the final movement of armature 34 is the result of the combined efforts of windings 63 and 64. When the current through winding 64 approaches its maximum or steady state value, also with a time delay of one-tenth to three-tenths of a second, for example, the attractive force produced by the magnetic field in core 62 overcomes the spring resisting force and the armature is moved to its final position to close the contacts of contact springs 51 and 52 and to open the contacts of contact springs 49 and 51. The time delay, in actuating the contact spring 51 to open and close the circuits associated therewith, is added to the time delays produced by windings 63, 106 and 107 and hence external circuits connected to the terminals 144 and 145, and 145 and 146 are opened and closed respectively after a time delay of the order of nine-tenths to one and two-tenths seconds, for example. Through variations in the variable resistor 116, the time delay produced by the winding 63 may be varied from one-tenth to three-tenths of a second, for example.

The two time delay units 29 and 31 are provided with four armature actuating coils, two of which are associated with each time delay unit. After the first circuit is energized, contacts are closed by it after the time delay within the coil necessary to build up its current to substantially a maximum or steady state value has been realized. Thereafter each winding, after the time delay which it produces, closes contacts energizing a succeeding coil also producing a time delay. Thus the windings are energized successively and the time delays of each winding are added to those of the remaining windings to produce a total time delay which is the sum of the individual time delays.

Referring to Fig. 8, there is shown a circuit diagram of another embodiment of the invention having substantially the same basic features as the embodiment already described, but in which a different arrangement is employed for varying the time delays produced by the individual windings. The second embodiment also includes two time delay units, each of which embodies two coils adapted to be externally energized along with short-circuited windings magnetically coupled therewith to assist in producing the desired time delays, and contact springs adapted to be operated by the various windings so as to energize the windings in succession and thereby add the time delays to each other.

The first of these time delay units comprises

an iron core 172 having the windings 173 and 174 arranged on it for external energization and the short-circuited windings 175 and 176. Associated with windings 173 and 174 are contact springs 177, 178, 179, and 180 which are provided with arc-resistant contacts to close circuits energizing certain of the time delay windings. The second time delay unit is substantially identical with the first and includes an iron core 182, with windings 183 and 184 arranged on it to be externally excited, and the short-circuited windings 185 and 186. Associated with this time delay unit are contact springs 187 and 188 which are provided with arc-resistant contacts for energizing one of the time delay circuits. In order to vary the time delay effected by the windings 173 and 183 and the coupled short-circuited windings, a resistor 189 is connected so as to be in series with each of windings 173 and 183, and to vary the time delay produced by the windings 174 and 184 along with the coupled short-circuited windings, a resistor 191 is connected so as to be in series with windings 174 and 184. The switch 192 and a source of current supply, which may be a battery 193, are arranged to energize the windings of the time delay units.

The coil 173 is energized through a circuit extending from the source of current supply 193, through switch 192, conductor 194, variable resistor 189, conductor 195, winding 173, conductor 196, conductor 197, and conductor 198 to current source 193. The remaining externally excited time delay windings are energized through contacts controlled by preceding windings and hence remain unenergized in the first instance. The current through winding 173 increases dependent on its own resistance and inductance, the resistance and inductance reflected into the circuit by the coupled short-circuited windings 175 and 176, and the resistance of the resistor 189, according to the law as set forth for the first embodiment. When this current reaches substantially its steady state or maximum value, only the contacts of contact springs 177 and 178 are closed to energize succeeding winding 183. Varying the value of resistor 189 of course varies the time delay which elapses before the contact springs 177 and 178 are actuated by winding 173.

Closing the contacts of contact springs 177 and 178 energizes winding 183 through a circuit extending from the source of supply 193, switch 192, through conductor 194, resistor 189, conductor 199, winding 183, conductor 201, contact springs 177 and 178, conductor 202, conductor 197, and conductor 198 to source of supply 193. With the completion of this circuit, the current through winding 183 increases dependent on its own resistance and inductance, the resistance and inductance reflected into the circuit by the coupled short-circuited coils 185 and 186, and the resistance of resistor 189. When this current reaches substantially its steady state or maximum value, the contact springs 187 and 188 are actuated to energize winding 174. The resistor 189 being variable, the time delay produced by winding 183 may be varied. However, since the resistor 189 also varies the time delay in winding 173, when this resistor once has its value selected, it introduces virtually the same variation in time delay into both the windings 173 and 183.

Closing the contacts of contact springs 187 and 188 energizes winding 174 through a circuit extending from source of supply 193, through switch 192, conductor 194, resistor 191, conductor 203, winding 174, conductor 204, contact springs 187

and 188, conductor 205, conductor 206, and conductor 198 to source of supply 193. After winding 174 is energized, the current begins to build up therein and creates a magnetic field through the iron core 172 in addition to that created by winding 173. The increase in the current is dependent upon the resistance and inductance of winding 174 and the resistance and inductance reflected into the circuit by the coupled short-circuited windings 175 and 176, and the variable resistance 191. When this current reaches its steady state or maximum value, the contacts of contact springs 179 and 180 are closed. The time delay, in actuating contact springs 178 and 180, may be varied by varying the value of resistor 191.

Closing contacts of contact springs 179 and 180 energizes winding 184 through a circuit extending from the source of supply 193, through switch 192, conductor 194, resistor 191, conductor 207, winding 184, conductor 208, contact springs 179 and 180, conductor 209, conductor 206, and conductor 198 to the current source 193. After the current flowing through winding 184 has increased to substantially its maximum or steady state value, the contact springs 211 and 212 are actuated, which may control an external circuit. The time delay in winding 184 is the result of its own resistance and the inductance as well as of the resistance and inductance reflected into the circuit by the coupled short-circuited windings 185 and 186, and the resistor 191. The winding 183 is still energized and thus the contact springs 211 and 212 are closed through the combined efforts of windings 183 and 184. By varying the resistance of resistor 191, the time delay produced by winding 184 may be varied, but since resistor was set to vary the time delay of the winding 174, it produces substantially the same time delay in winding 184. In the second embodiment, as well as in the first one, the various windings of the time delay units are successively energized and the time delay of each winding is added to that of the succeeding windings to produce a total time delay equal to the sum of the individual time delays, contacts being arranged to be actuated by each winding after its time delay.

Figs. 9, 10 and 11 indicate schematically different arrangements for producing time delays within the windings of the time delay units. In Fig. 9 there is shown an iron core 213 having two coils 214 and 215 wound thereon and arranged to be excited from an external source, and a short-circuited winding 216 also wound on core 213 and therefore magnetically coupled to windings 214 and 215, the windings 214, 215 and 216 being separately wound. Assuming that winding 214 is energized first, current will build up therethrough dependent on its own resistance and inductance as well as the resistance and inductance reflected into the circuit from the short-circuited winding 216. After the current in winding 214 reaches its maximum or steady value, there will be no change in the current flowing, and hence, there will be no current flowing in winding 216. Thereafter, when winding 215 is energized, the current therein will increase dependent on its own inductance and resistance, as well as that reflected into the circuit from the winding 216. Current flows in winding 216 as a result of its also being coupled with winding 215, and hence, it produces the same time delay in connection with winding 215 as it did in connection with winding 214. In this manner a

single winding may be used to produce time delays in more than one winding coupled with it.

Fig. 10 illustrates an arrangement having an iron core 217, two externally excitable windings 218 and 219, and a short-circuited winding 221, all three windings being wound together on core 217. In this modification, short-circuited winding 221 acts in conjunction with each of windings 218 and 219 to produce time delays, but the interwinding of the windings brings them closer together and creates a state of more effective coupling.

In Fig. 11 there is shown an arrangement for producing time delays in coils having an iron core 222, two windings 223 and 224 interwound with each other, and a conducting slug 225 which may be of copper or some other good conducting material. The copper slug 225 is continuous and may, for example, be a cylindrical slug surrounding core 222, and accordingly forms a short-circuited path for currents flowing therein, the slug accordingly producing a time delay in the build-up of the currents through windings 223 and 224.

Without further elaboration, the foregoing will so fully explain the gist of my invention that others may, by applying current knowledge, readily adapt the same for use under varying conditions of service, without eliminating certain features, which may properly be said to constitute the essential items of novelty involved, which items are intended to be defined and secured to me by the following claims.

I claim:

1. Time delay apparatus comprising, a pair of coils arranged on a core, said coils being separately and successively energizable and being so wound as to produce, when energized, cumulative excitation of said core, means for conducting energization to one of said pair of coils, time delay circuit means arranged on said core and being magnetically coupled with said coils, an armature actuatable by said pair of coils, said armature having one position effected by energization of one of said pair of coils and having another position effected by energization of both of said pair of coils, resilient means resisting actuation of said armature, said resilient means having sufficient stiffness to permit actuation of said armature only to said one position after energization of said one coil, contacts actuatable by said armature in moving to said one position, circuit means made effective by the actuation of said contacts for conducting energization to the other of said pair of coils, said resilient means further having such stiffness to permit actuation of said armature to said other position after energization of said other coil.

2. Time delay apparatus comprising, a pair of coils arranged on a core, said coils being separately and successively energizable and being so wound as to produce, when energized, cumulative excitation of said core, means for conducting energization to one of said pair of coils, time delay circuit means arranged on said core and being magnetically coupled with said coils, a first armature actuatable by said pair of coils, said first armature having one position effected by energization of one of said pair of coils and having another position effected by energization of both of said pair of coils, resilient means having sufficient stiffness to permit actuation of said first armature only to said one position after energization of said one coil, first contacts actuatable by said armature in moving to said one position, a

third coil arranged on a further core, time delay circuit means mounted on said further core and being magnetically coupled with said third coil, a second armature actuatable by said third coil when energized, circuit means connecting said first contacts to said third coil for conducting energization thereto upon actuation of said first contacts, second contacts actuated by said second armature when said third coil is energized, and circuit means connecting said second contacts to the other of said pair of coils for conducting energization thereto upon actuation of said second contacts, said resilient means further having such stiffness to permit actuation of said first armature to said other position after energization of said other coil.

3. Time delay apparatus comprising, a first pair of coils arranged on a first core, each of said first pair of coils being separately and successively energizable and being so wound as to produce, when energized, cumulative excitation of said first core, means for conducting energization to one of said first pair of coils, time delay circuit means arranged on said first core and being magnetically coupled with said first pair of coils, a first armature actuatable by said pair of coils, said first armature having one position effected by energization of one of said first pair of coils and having another position effected by energization of both of said pair of coils, first resilient means having sufficient stiffness to permit actuation of said first armature only to said one position after energization of said one coil of said first pair, first contacts actuatable by said first armature in moving to said one position, a second pair of coils arranged on a second core, each of said second pair of coils being separately and successively energizable and being so wound as to produce, when energized, cumulative excitation of said second core, time delay circuit means arranged on said second core and being magnetically coupled with said second pair of coils, a second armature actuatable by said second pair of coils, said second armature having one position effected by energization of one of said second pair of coils and having another position effected by energization of both of said second pair of coils, second resilient means having sufficient stiffness to permit actuation of said second armature to said one position after energization of said one coil of said second pair, circuit means connecting said first contacts to said one coil of said second pair for conducting energization thereto upon actuation of said first contacts, second contacts actuated by said second armature when said one coil of said second pair is energized, circuit means connecting said second contacts to the other of said first pair of coils for conducting energization thereto upon actuation of said second contacts, said first resilient means further having such stiffness to permit actuation of said first armature to its other position after energization of said other coil of said first pair, third contacts actuatable by said first armature in moving to its other position, circuit means connecting said third contacts to the other coil of said second pair for conducting energization thereto upon actuation of said third contacts, said second resilient means further having such stiffness to permit actuation of said second armature to said other position after energization of said other coil of said second pair.

4. Time delay apparatus comprising, a pair of coils arranged on a core, said coils being separately and successively energizable and being so

wound as to produce, when energized, cumulative excitation of said core, means for conducting energization to one of said pair of coils, time delay circuit means including a short circuited winding arranged on said core and being magnetically coupled with said coils, an armature actuatable by said pair of coils, said armature having one position effected by energization of one of said pair of coils and having another position effected by energization of both of said pair of coils, resilient means resisting actuation of said armature, said resilient means having sufficient stiffness to permit actuation of said armature only to said one position after energization of said one coil, contacts actuatable by said armature in moving to said one position, circuit means made effective by the actuation of said contacts for conducting energization to the other of said pair of coils, said resilient means further having such stiffness to permit actuation of said armature to said other position after energization of said other coil.

5. Time delay apparatus comprising, a pair of coils arranged on a core, said coils being separately and successively energizable and being so wound as to produce, when energized, cumulative excitation of said core, means for conducting energization to one of said pair of coils, time delay circuit means arranged on said core and being magnetically coupled with said coils, an armature actuatable by said pair of coils, said armature having one position effected by energization of one of said pair of coils and having another position effected by energization of both of said pair of coils, resilient means resisting actuation of said armature, said resilient means having sufficient stiffness to permit actuation of said armature only to said one position after energization of said one coil, contacts actuatable by said armature in moving to said one position, circuit means made effective by the actuation of said contacts for conducting energization to the other of said pair of coils, said resilient means further having such stiffness to permit actuation of said armature to said other position after energization of said other coil, and resistance means connected in circuit with at least one of said pair of coils for varying the time delay of the apparatus.

6. Time delay apparatus comprising, a first pair of coils arranged on a first core, each of said first pair of coils being separately and successively energizable and being so wound as to produce, when energized, cumulative excitation of said first core, means for conducting energization to one of said first pair of coils, time delay circuit means arranged on said first core and being magnetically coupled with said first pair of coils, a first armature actuatable by said pair of coils, said first armature having one position effected by energization of one of said first pair of coils and having another position effected by energization of both of said pairs of coils, first resilient means having sufficient stiffness to permit actuation of said first armature only to said one position after energization of said one coil of said first pair, first contacts actuatable by said first armature in moving to said one position, a second pair of coils arranged on a second core, each of said second pair of coils being separately and successively energizable and being so wound as to produce, when energized, cumulative excitation of said second core, time delay circuit means arranged on said second core and being magnetically coupled with said sec-

ond pair of coils, a second armature actuatable by said second pair of coils, said second armature having one position effected by energization of one of said second pair of coils and having another position effected by energization of both said second pair of coils, second resilient means having sufficient stiffness to permit actuation of said second armature to said one position after energization of said one coil of said second pair, circuit means connecting said first contacts to said one coil of said second pair for conducting energization thereto upon actuation of said first contacts, second contacts actuated by said second armature when said one coil of said second pair is energized, circuit means connecting said second contacts to the other of said first pair of coils for conducting energization thereto upon actuation of said second contacts, said first resilient means further having such stiffness to permit actuation of said first armature to its other position after energization of said other coil of said first pair, third contacts actuatable by said first armature in moving to its other position, circuit means connecting said third contacts to the other coil of said second pair for conducting energization thereto upon actuation of said third contacts, said second resilient means further having such stiffness to permit actuation of said second armature to said other position after energization of said other coil of said second pair, resistance means connected in circuit with one coil of each of said first and second pairs of coils, and further resistance means in circuit with the other coil of each of said first and second pairs of coils.

7. Time delay apparatus comprising, a pair of coils interwound on a core, said coils being separately and successively energizable and being so wound as to produce, when energized, cumulative excitation of said core, means for conducting energization to one of said pair of coils, time delay circuit means including a short circuited winding interwound with said pair of coils on said core and being magnetically coupled with said coils, an armature actuatable by said pair of coils, said armature having one position effected by energization of one of said pair of coils and having another position effected by energization of both of said pair of coils, resilient means resisting actuation of said armature, said resilient means having sufficient stiffness to permit actuation of said armature only to said one position after energization of said one coil, contacts actuatable by said armature in moving to said one position, circuit means made effective by the actuation of said contacts for conducting energization to the other of said pair of coils, said resilient means further having such stiffness to permit actuation of said armature to said other position after energization of said other coil.

8. Time delay apparatus comprising, a pair of coils interwound on a core, said coils being separately and successively energizable and being so wound as to produce, when energized, cumulative excitation of said core, means for conducting energization to one of said pair of coils, time delay circuit means including a conductive mass mounted on said core and being magnetically coupled with said coils, an armature actuatable by said pair of coils, said armature having one position effected by energization of one of said pair of coils and having another position effected by energization of both of said pair of coils, resilient means resisting actuation of said armature, said resilient means having sufficient stiff-

ness to permit actuation of said armature only to said one position after energization of said one coil, contacts actuatable by said armature in moving to said one position, circuit means made effective by the actuation of said contacts for conducting energization to the other of said pair of coils, said resilient means further having such stiffness to permit actuation of said armature to said other position after energization of said other coil.
